By *A. Randolph, Jr.* Attorney

UNITED STATES PATENT OFFICE.

HENRY RICHARD WRIGHT, OF PHILADELPHIA, PENNSYLVANIA.

BLACKING BOX.

Application filed August 18, 1921. Serial No. 493,233.

To all whom it may concern:

Be it known that I, HENRY RICHARD WRIGHT, a citizen of the United States, residing at Philadelphia, in the county of 5 Philadelphia and State of Pennsylvania, have invented certain new and useful Improvements in Blacking Boxes; and I do hereby declare the following to be a full, clear, and exact description of the invention, 10 such as will enable others skilled in the art to which it appertains to make and use the same.

This invention has relation to certain new and useful improvements in boxes and 15 jars for containing blacking, jelly, salve, etc., and has for its primary object the provision of a box which will be provided with a resilient strip connected with the cover to form a handle to assist in removing the 20 same but connected in such a manner as not to interfere with compact packing of the boxes.

The invention has for another object the 25 provision of a box of the character stated in which a spring or resilient strip may conform to the outer wall of the box closure or cover and rest in a groove or buckle receiving member when the cover is in closed position upon the box.

30 The invention has for another object the provision of a box of the character stated which will be of extremely simple construction, inexpensive to manufacture and which may be readily opened or closed, as desired. 35 With the foregoing and other objects in view as will appear as the description proceeds, the invention consists in the combination and arrangement of cooperating elements as hereinafter more specifically set forth, claimed and shown in the accompanying drawings forming a part of the present application and in which:

Figure 1 is a plan view of the improved box with my attachment applied thereto.

45 Figure 2 is a sectional view on the plane of line 2—2 of Figure 1.

Figure 3 is a detail view, showing the manner of securing the resilient member to the cover.

50 Figure 4 is a sectional view showing the manner in which the resilient member rests in a groove when the cover is in closed position upon the box.

Referring more in detail to the drawings 55 in which similar reference characters design-

inate corresponding parts throughout the several views, 1 indicates a box section or receptacle, and 2 a detachable cover or closure therefor, which parts are to be taken as of conventional form. 60

In carrying out the present invention I employ a resilient member formed of a strip of resilient metal or the like and designated by the numeral 3. One end of this member 3 is secured to the cover 2, as shown at 4 65 while the opposite end 5 is left free and adapted to be slidably received within a buckle 6 or the like secured upon the side of the closure 2 and rest in the groove 7 of said buckle or receiving member 6, as 70 shown in the drawings. When it is desired to employ the member 3 for removing the cover 2, however, the end 5 may be pulled outwardly to the dotted line position of Figure 1 to space the central portion thereof from the closure 2 and then grasped as a handle with the operator's fingers extending through said space and the handle or strip then moved in a direction transversely of and away from the box section 1. The engagement between the buckle 6 and strip 3 prevents turning of strip 3 on rivet 4 as a pivot. End 5 terminates in a hook which abuts and limits outward sliding movement of said free end of the 85 strip, as suggested in Figure 1.

From the foregoing paragraphs taken in connection with the accompanying drawings, it will be seen that I have provided a simple form of box in which the cover may 90 be readily extracted from the box 1 or secured thereon and when the cover 2 is in position, the resilient member 3 will not interfere with ready handling of the box.

While the preferred embodiment of the 95 invention has been shown and described, it will be understood that minor changes in the details of construction and arrangement of parts may be resorted to within the scope of what is claimed without departing from the 100 spirit of the invention.

What is claimed is:—

1. A closure having a strip operable to open the same, said strip conforming substantially to the shape of the side wall of 105 the closure and adapted to normally fit thereagainst, means to connect the strip and closure whereby they will move unitarily in a direction transversely of the closure, and said strip at a portion thereof being capable 110

of projection outwardly from said wall to afford greater operating leverage for the strip.

2. A closure having a strip operable to open the closure, said strip being contractile and arcuate to an extent greater than a semi-circle, said strip conforming substantially to the shape of the side wall of the closure and adapted to normally fit thereagainst, 10 means to secure said strip adjacent one end to the closure, the other end of the strip having an outwardly extending hook, said strip at a portion thereof being capable of projection outwardly from said wall to af-

ford greater operating leverage for the 15 strip, a buckle on said closure through which said strip passes, and said buckle being arranged in advance of said hook in the closed position of the strip whereby the hook and buckle will coact to limit the outward projection of the strip. 20

In testimony whereof I affix my signature in presence of two witnesses.

HENRY RICHARD WRIGHT.
